UNITED STATES PATENT OFFICE

113,382

DESIGN FOR A TABLE MAT FOR A DRINKING GLASS OR THE LIKE

Wilhelm J. Fischbein, Cologne, Germany

Application September 27, 1938, Serial No. 80,111
In Germany June 3, 1938

Term of patent 3½ years

To all whom it may concern:

Be it known that I, Wilhelm J. Fischbein, a German citizen, residing at Cologne, Germany, have invented a new, original, and ornamental Design for a Table Mat for a Drinking Glass or the like, of which the following is a specification, reference being had to the accompanying drawing, forming a part thereof.

In the drawing:

The figure is a perspective view of the table mat for a drinking glass or the like showing my design.

The shading of the outer part of the mat indicates a color which contrasts from the color of the inner part of the mat.

I claim:

The ornamental design for a table mat for a drinking glass or the like, as shown and described.

WILHELM J. FISCHBEIN.
